UNITED STATES PATENT OFFICE

114,800

DESIGN FOR AN EYE GOGGLE FRAME

Raymond Simon, Chicago, Ill., assignor to New Era Optical Company, Chicago, Ill., a corporation of Illinois

Application August 15, 1938, Serial No. 79,345

Term of patent 3½ years

To all whom it may concern:

Be it known that I, Raymond Simon, a citizen of the United States, residing in the city of Chicago, county of Cook, and State of Illinois, have invented a new, original, and ornamental Design for an Eye Goggle Frame, of which the following is a specification, reference being had to the accompanying drawing, forming a part thereof, and in which

Fig. 1 is a front view of an eye goggle frame showing my new design;

Fig. 2 a side view; and

Fig. 3 a perspective view thereof.

I claim:

The ornamental design for an eye goggle frame, as shown.

RAYMOND SIMON.
